(57) **CLAIM**

The ornamental design for an electric drying rack, as shown and described.

DESCRIPTION

FIG. 1 is a perspective view of an electric drying rack showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the selected portion 8 in FIG. 7;

FIG. 9 is an enlarged view of the selected portion 9 in FIG. 7; and,

FIG. 10 is an enlarged view of the selected portion 10 in FIG. 7.

The dash-dash lines show portions of the electric drying rack that form no part of the claimed design. The dash-dot lines in FIGS. 7-10 illustrate the boundary of the enlarged views and form no part of the claimed design.

1 Claim, 10 Drawing Sheets
